(57) **CLAIM**

The ornamental design for an winch mounting platform, as
shown and described.

DESCRIPTION

FIG. 1 shows a front prospective view of an integrated solenoid winch mount of the present invention attached to a winch;

FIG. 2 shows a front prospective view of the integrated solenoid winch mount as shown in FIG. 1 by itself and not attached to a winch;

FIG. 3 shows a rear prospective view of the integrated solenoid winch mount as shown in FIG. 1 attached to a winch;

FIG. 4 shows a rear prospective view of the integrated solenoid winch mount as shown in FIG. 2;

FIG. 5 shows a front view of the integrated solenoid winch mount as shown in FIG. 2;

FIG. 6 shows a rear view of the integrated solenoid winch mount as shown in FIG. 2;

FIG. 7 shows a top view of the integrated solenoid winch mount as shown in FIG. 2;

FIG. 8 shows a bottom view of the integrated solenoid winch mount as shown in FIG. 2;

FIG. 9 shows a left side view of the integrated solenoid winch mount as shown in FIG. 2; and,

FIG. 10 shows a right side view of the integrated solenoid winch mount as shown in FIG. 2.

The broken lines shown in the drawings are for the purpose
of illustrating environmental structure and form no part of
the claimed design.
